AU 291 EX

OR D 9,962

Design No. 9,962, dated May 8, 1877

FIG. 1.

FIG. 2.

No. 606.

UNITED STATES PATENT OFFICE.

JAMES MORGAN, OF BROOKLYN, NEW YORK.

DESIGN FOR A MONUMENT.

Specification forming part of Design No. 9,962, dated May 8, 1877; application filed April 27, 1877.
[Term of Patent 7 years.]

To all whom it may concern:

Be it known that I, JAMES MORGAN, of Brooklyn, county of Kings, and State of New York, have invented a Design for a Monument, of which the following is a specification:

The nature of my design is fully shown in the accompanying drawing, to which reference is made, and in which—

Figure 1 is a front view, and Fig. 2 a side view, of the monument.

Similar letters of reference indicate corresponding parts.

The design relates to a monument for graves; and consists of base stones or steps, a middle diminishing section, and side-projecting top section, with plain tapering cap and side ridges.

In the drawing, A A are the base stones or steps, of diminishing size and height, and connected with each other and with the middle section B by intermediate tapering parts a.

The middle section B has a square lower part and a slightly tapering upper part, connected therewith by concave side moldings b. The top C is slightly enlarged by sidewise-projecting moldings d and a square portion, f, having a cup tapering from the sides to the center, and having ridges g, beveling off from their center lines toward the front and rear sides of the top, as shown clearly in Fig. 2.

Having thus described my invention, I claim as new and desire to secure by Letters Patent—

The design for a monument, formed of a base of steps with intermediate tapering parts, of a middle section with slightly-diminishing upper part, and of a top with projecting side molding, tapering cap, and beveled side ridges, substantially as shown and described.

JAMES MORGAN.
